UNITED STATES PATENT OFFICE.

ARTHUR A. JOHNSON, OF WASHINGTON, DISTRICT OF COLUMBIA, ASSIGNOR TO
UNDERWOOD TYPEWRITER COMPANY, OF NEW YORK, N. Y., A CORPORATION OF
DELAWARE.

TYPEWRITING MACHINE.

Application filed July 12, 1921. Serial No. 484,048.

To all whom it may concern:

Be it known that I, ARTHUR A. JOHNSON, a citizen of the United States, residing in Washington, District of Columbia, have invented certain new and useful Improvements in Typewriting Machines, of which the following is a specification.

This invention relates to typewriting machines, and is herein disclosed as applied to 10 an Underwood standard typewriting machine of the continuous billing or fan-fold type, one form of which is disclosed in the patent to Wernery & Smith, No. 1,132,055, dated March 16, 1915.

15 In a machine of the type referred to, the plies of fan-fold webs, or separate webs, are led between blades on a shiftable carbon-carrier, so that carbon-sheets, secured at their rear ends to the blades, will be inter-

20 leaved between the various plies or webs. The webs or plies then pass over the rear table and between the platen and feed-rolls to the printing line. In connection with typing on the forms usually carried by the

25 superposed webs in use in such machines, the webs and interleaved carbon-sheets are fed past the printing line and delivered on a front paper-table, the carbon-carrier being drawn forward during this operation. Upon

30 completion of the typing on a given set of superposed forms, a frame, carrying the platen and front paper-table, is swung forwardly to raise the platen from the feed-rolls, and the forward ends of the webs,

35 which have been grasped by the operator, are drawn forward to gaging position. The carbon-carrier is then shifted to the rear to bring the carbon-sheets between unused portions of the webs, and the platen and paper-

40 table are returned to their normal positions, the used forms being severed over a knife which is usually provided. Typing may then be effected upon another set of superposed forms. When separate webs are used,

45 the superposed forms are moved out of alignment by creeping of the webs in being fed around the revolute platen.

The main object of the invention is to provide means to prevent cumulative creeping by realigning the forms at regular in-

tervals, and also to advance the webs automatically to gaging positions.

According to the embodiment of the invention herein disclosed, provision is made of a link pivoted on a bracket mounted on 55 a front bar of the typewriter-carriage. The link may be swung rearwardly into engagement with the front paper-table, and has pivoted at its free end a re-registering element, comprising two pins end engaging portions to rest against the front paper-table, the re-registering element being urged by suitable means, such as a spring, to a position such that the link will normally be supported so that the registering pins will be 60 held above the table, to permit the passage of the webs. When, however, it is desired to raise the platen, the registering element is pressed lightly against the webs; during the swinging movement, the pins entering 65 the perforations immediately, if in register therewith, or, in case the perforations have been advanced to a point beyond the registering pins, creeping upwardly relatively to the sheets during the swinging of the 70 platen to its upper position, and entering the perforations when brought into register therewith. The sheets will then advance along a bar, which may be the usual gage-bar, until the swinging movement of the 75 link and front paper-table is checked by engagement of the link with a stop, preferably forming part of the bracket on which the link is pivoted.

Provision may also be made of a clamping device, slidably mounted on the bar forming an extension of the front paper-table, and of means to secure the clamping device in an adjusted position on the bar. Detent means may be provided to hold the clamp in ineffective position or in effective position to hold the leading ends of the work-webs against the bar. The link and the clamp may be provided with suitable co-operating means, so that, upon movement 85 of the registering element to its extreme position, due to swinging of the front paper-table, the clamping device will be rendered effective to hold the leading ends of the webs in gaged position.

The link may be composed of two parts, connected so that the length of the link may be varied, and, in one form of the invention, the parts may be secured to each other in adjusted position. In another form of the invention, provision may be made of means to automatically vary the length of the link when the link is swung forwardly with the front paper-table.

10 Other features and advantages will hereinafter appear.

In the accompanying drawings,

Figure 1 is a sectional side view, showing my invention applied to so much of an 15 Underwood typewriting machine of the fan-fold type as is necessary for the purpose of illustration.

Figure 2 is a fragmentary view, showing the registering device brought into co-operation with the perforations at the head of a 20 set of forms and the webs slightly advanced, due to the forward swinging of the platen.

Figure 3 is a view similar to Figure 2, but showing the parts in the position assumed when the platen has been lifted, the 25 clamping device having been rendered effective to hold the leading ends of the webs.

Figure 4 is a plan view of the invention.

Figure 5 is a view showing a modified 30 form of the invention, in which provision is made of means to vary the length of the link during the swinging movement from the position shown in Figure 5 to that shown in Figure 3.

35 A platen 10 is carried by an axle 11 journaled in ends 12 of a swing-frame or platen-frame 13 which comprises a front paper-table 14. The ends 12 are pivotally mounted on a rod 15 supported by a carriage 16 which comprises ends 17 and a rear paper-table 18 cut away beneath the platen to 40 form fingers 19 between which lie feed-rolls 20 to co-operate with the platen. The paper-table 18 is bent upwardly and rearwardly back of the platen, so that it overlies a transverse rod 21 on which arms 22, projecting from the platen-frame ends 12, rest when the platen-frame is in its normal position.

45 Extending rearwardly from the carriage 16 is an extension supported at its forward end on a bar 23 which forms part of the carriage-frame. This extension comprises front and rear rods 24 and 25, respectively, and rods 26 connecting the same, the last-mentioned rods serving to support rails 27 which cooperate with grooved rolls 28 on the base plate 29 of carbon-carrier 30 to guide the latter in its forward and rearward movement. The carbon-carrier comprises the usual stepped supports 31, with blades 32 extending inwardly therefrom, and an arm 33 at one side thereof and extending toward the front of the machine. Preferably, the arm 33 is provided at its forward

end with a finger-piece 34. The mechanism so far described is similar to that of machines in general use.

The present invention is designed for use with separate webs 35 having perforations 36 near the leading ends of the forms with which the webs are provided. In carrying out the invention, the front bar 37 of the carriage is utilized to support a bracket 38, preferably formed of a single piece of sheet-metal. The bracket 38 is provided with a flat portion 39 to rest on the upper surface of a horizontal flange of the bar 37, and with a curved portion 40 so shaped as to fit over the forward edge of the flange, whereby, when the bracket is placed in position on the bar 37 and secured thereto by a screw 41, it will be held firmly in position. The bracket 38 is also provided with an upwardly-extending ear 42 and a forwardly-extending finger 43. Pivoted at 44 in the ear 42 is a two-part link 45, the two parts 46 and 47 of which are connected so that the length of the link may be varied. To this end, the part 47 is provided with a horizontal slot 47a, and the part 46 with pins which may be in the form of set-screws 48 extending through the slot.

At the free end of the part 47 is attached an aligning device consisting of a head 49, preferably formed of a single piece of sheet-metal having a yoke 50 placed over the end of the part 47 and pivotally secured thereto by a bolt 51 and a nut 52. A spring 53 attached at one end to a pin 54 on the part 47, and at the other end to a pin 55 on the yoke 50, tends to turn the yoke about the bolt 51, so that the head 49 will be supported by engaging fingers 56 thereon and the register pins 57 will be maintained above the webs as they are fed forwardly thereunder. The movement of the head 49 under the action of the spring 53 may be limited by a stop 57a attached to the head in any suitable manner. To facilitate the action of the register pins 57, the front paper-table 14 is provided with slots 58 lying beneath the paths of the register pins 57, and, in order to prevent undue weakening of the paper-table 14 along these slots, U-shaped 115 brackets 59 are fastened to the paper-table at the lower side, the depth of the channels in these brackets being such as to prevent any interference with the register pins 57.

120 Mounted on a bar 60 secured to the rear of the paper-table 14 and forming a central extension thereof, is a gripping device designated as a whole by 61. The gripping device 61 comprises a plate 62 at the rear of the bar 60, having a longitudinal slot 63 through which passes a pin 64 projecting from the rear face of the bar 60, provision being made of a nut 65 threaded on the outer end of pin 64, so that the plate 62 may be secured in adjusted position on the bar 125 130

60. Extending rearwardly from the plate 62, near one edge of the bar 60, is an ear 66, on which is pivoted at 67 a lever 68. This lever extends along the lower side of the 5 bar 60 and then is curved upwardly and downwardly along the upper side of the bar, so that a finger 69 extending laterally from the lever near its free end may be utilized to press the leading ends of work-webs 10 35 against said bar. On the opposite side of pivot 67, the lever 68 is provided with two notches 71 with which co-operates a detent spring 72 to hold the lever 68 and finger 69 in either effective or ineffective position. 15

Whenever work of a given character is to be performed, webs 35 having suitable forms thereon are led over the rear rod 25 of the extension and through the carbon-carrier, so that carbon-sheets 73 attached to the blades 32 will be interleaved therebetween. The webs 35 are then drawn forward between the platen and the usual knife 74, when the platen is in its raised 20 position, as shown in Figure 3, and the platen returned to normal position, as shown in Figure 1. Typing may then be effected on the webs by types 75 on type-bars 76, the platen being line-spaced by 25 any suitable means (not shown). It will be understood that the gripping device 61 has been positioned on bar 60 corresponding to the length of the forms and secured in its adjusted position by means of the nut 65 30 threaded on the pin 64, and that a corresponding adjustment has been made between parts 46 and 47 by means of screws 48.

Upon completion of the typing on the 40 first set of forms, the aligning device is pressed towards the front paper-table 14, so that the pins 57 will enter the perforations 36 if in register therewith. If, however, the perforations have been carried past 45 the pins, the latter will, upon the forward swing of the frame 13, travel along the face of the outer web until brought into register with the perforations, whereupon they will enter the perforations. Upon further movement of the frame 13, the webs 35 will be advanced by the pins 57 until the frame 13 and link 45 are checked in their forward movement by engagement of the link with the finger 43, the parts then assuming the 50 positions shown in Figure 3. The bolt 51 will, as the link 45 approaches its limiting position, engage a cam 77 on the lever 68 and move the finger 69 in a direction to clamp the leading ends of the webs against the bar 60, the lever 68 being held in effective position by the spring 72 engaging in the upper notch 71, as shown in Figure 3. 55

The carbon-carrier may then be returned to its normal position by means of finger-piece 34 and the frame 13 swung to its nor-

mal position, the link 45 being left in its forward position. It will be evident that, when the paper-table 14 is in its Figure 3 position, the pins 57 will be maintained in the perforations 36 in the leading ends of 70 the webs and will be sufficient to hold the webs during the rearward movement of the carbon-carrier. The gripping device 61 is also effective at this time, but is of value 75 chiefly to hold the leading ends of the webs in position on the bar 60 during the restoration of the platen to its normal position. When the frame 13 is swung to the rear, the webs 35 are lifted from the pins 57 and are held in position on the bar 60 by the gripping device 61, the link 45 being left in its forward position. Upon shifting the lever 68 manually to release the leading ends of the forms just typed, the webs may be severed by drawing the same across the knife 74, the link 45 swung to its Figure 1 position, and the typing of the next set of forms begun. During this typing, the link 45 is normally in the position shown in Figure 1, being supported in such position by the 80 fingers 56 which rest on the outer web. 85

According to a modified form of the invention, provisions may be made of means to change the length of the link 45 automatically during the forward swinging movement of the frame 13. In this form, the screws 48, or corresponding elements, do not clamp the parts 46 and 47 together, but, with the slot 47^a, furnish a sliding connection between the parts 46 and 47 so as to permit movement 90 therebetween. The means for automatically varying the length of the link 45 may comprise a toggle, one member 78 of which is pivoted to part 47 at 79, and the other member 80 pivoted on the pivot 44 of the part 46. The members 78 and 80 are connected by means of a pivot pin 81, and, since these members are on opposite sides of the part 46, a notch 82 is provided in the upper edge of the latter to receive pin 81 and permit the toggle to be straightened further than would otherwise be possible. It should be understood, however, that the toggle is not straightened sufficiently to prevent collapse of the link 45 under the action 100 of the spring when the link is swung rearwardly. The link 45 is normally held in collapsed condition by means of a spring 83 connecting the pivot 79 with the pivot 44. When the link 45, shown in Figure 5, is swung to the right, its length will not be varied until the member 80 is brought into contact with the finger 43 on the front bar 37 of the typewriter-carriage. Further movement, however, of the link will cause 105 the toggle, comprising members 78 and 80, to be straightened, and, when the link 45 reaches its limiting position, the straightening of the toggle will have been completed 110 and the link 45 extended to its greatest 115 120 125 130

length. The swing-frame 13 may then be restored to its normal position, the gripping device released, and, after severing the used portions of the webs, the link 45 restored 5 to its Figure 5 position.

It will be seen that the registering and advancing device comprising the link 45 and the pins 57 serves also to gage the leading edges of the webs.

10 The platen 10 is connected with the usual line-spacing mechanism at all times in a well-known manner, as for example, by a broad gear 84 loosely mounted on the rod 15 and meshing with a gear 85 fixed on the 15 platen-axle 11 and with a gear 86 fixed on a stub-shaft 87 actuable by the line-spacing mechanism.

20 Variations may be resorted to within the scope of the invention, and portions of the improvements may be used without others.

Having thus described my invention, I claim:

1. In a typewriting machine, in combination, a traveling carriage having a front 25 bar extending transversely thereof, a revolute platen, a platen-lifting swing-frame pivoted on said carriage, said frame comprising a front paper-table, and a link, having pins thereon, pivoted on said front bar 30 in front of the pivotal axis of the swing-frame, so that, when its free end is pressed against the front paper-table and said frame swung to lift the platen, the pins will enter perforations in the work-webs in use to 35 align superposed forms thereon and then advance the leading edges of the webs to predetermined positions.

2. In a typewriting machine, in combination, a traveling carriage having a front 40 bar extending transversely thereof, a revolute platen, a platen-lifting swing-frame pivoted on said carriage, said frame comprising a front paper-table and a bar constituting an extension thereof, a link having pins thereon and pivoted on said front bar 45 in front of the pivotal axis of said swing-frame, so that, when its free end is pressed against the front paper-table and the frame swung to lift the platen, the pins will enter perforations in the webs in use 50 to align superposed forms thereon and then advance the leading edges of the webs to predetermined positions, and a clamp on said bar to grip the ends of said webs when 55 the leading edges thereof have been advanced to their limiting positions.

3. In a typewriting machine, in combination, a traveling carriage having a front bar 60 extending transversely thereof, a revolute platen, a platen-lifting swing-frame pivoted on said carriage, said frame comprising a front paper-table and a bar constituting an extension thereof, a link, having pins thereon, pivoted on said front bar in front of 65 the pivotal axis of said swing-frame, so that,

when its free end is pressed against the front paper-table and the frame swung to lift the platen, the pins will enter perforations in the webs in use to align superposed forms thereon and then advance the leading edges 70 of the webs to predetermined positions, a clamp on said bar to grip the leading ends of said webs when advanced to their limiting positions, and provisions on said clamp and link whereby the latter will render the 75 former effective when the webs are advanced to their limiting positions.

4. In a typewriting machine, in combination, a traveling carriage having a front bar, a revolute platen, a platen-lifting swing-frame pivotally mounted in said carriage, said swing-frame comprising a front paper-table and a bar serving as a prolongation thereof, a link pivotally mounted on said front bar, a head pivotally mounted on the 80 link near its free end and having pins thereon in position to enter perforations in work-webs when brought into register therewith, and a spring urging said head to a position on said link such that the pins 85 will be held above said webs when the link is swung to bring the head against the webs, whereby, upon pressing the head against the webs, the spring will yield and permit the pins to enter the perforations with which they are brought into register by the swinging of the frame, the pins then serving to advance the webs automatically during the remainder of said swinging movement of 90 said frame.

5. In a typewriting machine, in combination, a traveling carriage, a revolute platen, a platen-frame comprising a front paper-table, said frame being so pivoted on the carriage that a forward swing of the frame 105 will lift the platen, a link pivoted on the front of the carriage, said link comprising two parts having a pin-and-slot connection so that they may be shifted longitudinally of each other, and pins on the free end of 110 said link, so that, when the link is swung rearwardly against the front paper-table and the platen-frame swung forwardly, the pins will advance along the paper-table and, after entering perforations in the work-webs in use, will advance the webs automatically.

6. In a typewriting machine, in combination, a traveling carriage, a revolute platen, a platen-frame comprising a front paper-table, said frame being so pivoted on the carriage that a forward swing of the frame will lift the platen, a link pivoted on the front of the carriage, said link comprising two parts having a connection such as to 120 permit relative shifting longitudinally of each other to vary the length of the link, pins on the free end of said link, so that, when the link is swung rearwardly against the front paper-table and the platen-frame 125

130

swung forwardly, the pins will advance along the paper-table and, after entering perforations in the work-webs in use, will advance the webs automatically, and means to lengthen said link during its forward swinging movement by effecting a relative shifting between the two parts thereof.

7. In a typewriting machine, in combination, a traveling carriage, having a front bar, a revolute platen, a platen-lifting swing-frame pivoted on said carriage, said frame comprising a front paper-table and a bar constituting an extension thereof, a link having pins thereon and pivoted on said 10 front bar in substantially the same horizontal plane as the pivotal axis of the swing-frame, so that, when its free end is pressed against the front paper-table and the frame swung to lift the platen, the pins will enter 15 perforations in the webs in use to align superposed forms thereon and then advance the leading edges of the webs to predetermined positions, a clamp on said bar to grip the leading ends of said webs when advanced to their limiting positions, provisions on said clamp and link whereby the latter will render the former effective when the webs are advanced to their limiting positions, and detent means to hold said clamp 20 in either effective or ineffective position.

8. In a typewriting machine, in combination, a traveling carriage, a revolute platen, a swing-frame for said platen pivoted on said carriage, said frame including a front 25 paper-table and a bar forming an extension of said table, and means to cooperate with the webs at their forward ends and automatically advance the webs when the swing-frame is swung to lift the platen, said means comprising a link having two parts shiftable longitudinally with respect to each other, and a toggle device operable by the swing-frame in its forward movement.

9. In a typewriting machine, in combination, a traveling carriage, a revolute platen around which webs having forms thereon may be led, means, including a swingable front paper-table and a bar forming an extension thereof, to enable the webs to be 40 straightened beneath the platen, means, including pins to engage in perforations in the webs at the leading ends of the forms, for automatically advancing the webs when the paper-table is swung forwardly, a leading- 45 end clamp on said bar, and means whereby the clamp will be rendered effective by the web-advancing means at the end of its effective movement.

10. In a typewriting machine, in combination, a traveling carriage, a revolute platen around which webs having forms thereon may be led, means, including a swingable front paper-table and a bar forming an extension thereof, to enable the webs to be 50 straightened beneath the platen, a leading-

end clamp adjustable along said bar, and means actuatable by the forward swing of the paper-table to advance said webs and render the clamp, when adjusted in suitable position on the bar, effective to grasp the leading ends of the webs so advanced. 70

11. In a typewriting machine, in combination, a traveling carriage, a revolute platen, a platen-lifting swing-frame comprising a front paper-table and a centrally-positioned bar forming an extension thereof, a link pivoted on the front of said carriage, a head pivoted on said link and extending on each side thereof, means, including a spring, connecting said link and said head, whereby the leading end of the head, when in engagement with the paper-table, will serve to support the link, and pins at the trailing end of said head and on opposite sides of said link, said pins being normally held above the paper-table by said spring, and said table being so formed along the paths of the pins that, when the spring is overcome by pressing the head toward the paper-table, the pins may pass below the surface of the paper-table and so remain during the traveling movement of the pins due to the forward movement of the swing-frame. 80 85 90

12. In a typewriting machine, in combination, a traveling carriage, comprising a front bar having a horizontal flange extending forwardly from the top thereof, a revolute platen, a platen-lifting frame pivoted on said carriage in front of the platen and comprising a front paper-table and a central extension thereof, a bracket having a flat lower face to rest on the top of said flange, a portion to fit around the forward edge of said flange to enable the bracket to be firmly fastened on the bar, an upwardly-extending ear and a forwardly and upwardly-extending stop-finger at one side of said ear, a link pivoted on said ear on the side toward the finger, so that, when swung forwardly, it will engage the finger, and a web-aligning 100 and advancing device on the free end of said link, comprising pins positioned so as to pass on opposite sides of said extension. 105 110

13. In a typewriting machine, in combination, a traveling carriage, a revolute platen carried thereby, a carbon-sheet carrier shiftably mounted on said carriage, means to permit work-webs extending around the platen to be straightened beneath the latter, including a swingable 115 platen-lifting frame, means, including pins to engage in perforations in the work-webs, whereby the leading edges of the work-webs may be aligned and superposed forms thereon brought into register, and then the webs advanced to gaging positions when the platen-lifting frame is swung forwardly, and means on said frame, rendered effective by said aligning and advancing means, to grasp the leading ends of the webs in 120 125 130

their advanced positions and hold the same in position on the swing-frame during the return movement of the latter after the rearward movement of the carbon-sheet carrier.

14. In a typewriting machine, in combination, a traveling carriage, a revoluble platen carried thereby, a carbon-sheet carrier shiftably mounted on said carriage, means, including a swingable platen-lifting frame, to permit work-webs extending around the platen to be straightened beneath the latter, web-holding means whereby the leading ends of the work-webs may be engaged and advanced when the platen-lifting frame is swung forwardly, and means on said platen-lifting frame, rendered effective by said web-holding means, to hold said leading ends during the return movement of the frame.

15. In a typewriting machine, in combination, a traveling carriage, a revoluble platen carried thereby, a carbon-sheet carrier shiftably mounted on said carriage, means, including a swingable platen-lifting frame, to permit work-webs extending around the platen to be straightened beneath the latter, and controlling means whereby the leading ends of the work-webs may be engaged and automatically advanced to gaging positions upon forward movement of said frame, held in gaged positions during the rearward movement of the carbon-sheet carrier, and released when the frame with the leading ends thereon is swung rearwardly.

16. In a typewriting machine, in combination, a traveling carriage, a revoluble platen carried thereby, a carbon-sheet carrier shiftably mounted on said carriage, means, including a swingable platen-lifting frame, to permit work-webs extending around the platen to be straightened beneath the latter, controlling means whereby the leading ends of the work-webs may be engaged and automatically advanced to gaging positions upon forward movement of said frame, held in gaged positions during the rearward movement of the carbon-sheet carrier, and released when the platen-lifting frame with the leading ends thereon is swung rearwardly, and means, rendered effective by said controlling means for holding the leading ends of the work-webs in position on the platen-lifting frame during the return movement of the latter.

17. In a typewriting machine of the fan-fold type, in combination, a traveling carriage, a revoluble platen carried thereby, a carbon-sheet carrier shiftably mounted on said carriage, means, including a swingable platen-lifting frame, to enable work-webs extending around the platen to be straightened beneath the latter, means to engage

and hold the leading ends of the work-webs, and means whereby said frame, when swung forwardly, will cause the engaging and holding means to advance the work-webs and gage their leading ends.

18. In a typewriting machine, the combination with a displaceable platen around which disconnected plies of work-web may be led, of a normally idle re-registering device for said plies mounted upon the machine, said device movable into perforations in the web, and a web support also mounted on the machine to co-operate with said device for acting upon the webs by means of their perforations to bring the leading edges of the webs into realignment.

19. In a typewriting machine, the combination with a displaceable platen around which disconnected plies of work-web may be led, of a normally idle re-registering device for said plies mounted upon the machine, said device movable into perforations in the web, a web support also mounted on the machine to co-operate with said device for acting upon the webs by means of their perforations to bring the leading edges of the webs into realignment, and means for enabling said re-registering device to advance the web preparatory to typing a succeeding form thereon.

20. In a typewriting machine, the combination with a platen around which disconnected plies of work-web may be led, of a displaceable frame for said platen, said frame displaceable between a typing position and a position for effecting longitudinal shifting of the web-plies, and means actuated by said frame for advancing the web-plies during the movement of said frame away from typing position.

21. In a typewriting machine, the combination with a platen around which disconnected plies of work-web may be led, of a displaceable frame for said platen, said frame displaceable between a typing position and a position for effecting longitudinal shifting of the web-plies, a normally idle re-registering device for said plies mounted upon the machine, said device movable into perforations in the web, a web support also mounted on the machine to co-operate with said device for acting upon the webs by means of their perforations to bring the leading edges of the webs into realignment, and means whereby said re-registering device is called into action by said platen-frame during movement of the latter away from typing position.

ARTHUR A. JOHNSON.
